UNITED STATES PATENT OFFICE

163,480

BELT OR SIMILAR ARTICLE

Charles S. Raucher, New York, N. Y.

Application June 16, 1950, Serial No. 10,560

Term of patent 3½ years

(Cl. D3—10)

To all whom it may concern:

Be it known that I, Charles S. Raucher, a citizen of the United States of America, residing in New York, county of New York, and State of New York, have invented a new, original, and ornamental Design for a Belt or Similar Article, of which the following is a specification, reference being had to the accompanying drawing, forming part thereof.

Fig. 1 is a fragmentary plan view of a belt or similar article, showing my new design.

Fig. 2 is an edge view thereof.

The portion of the belt not shown is similar in appearance to the body of the belt shown in Fig. 1 and continues around to form a circle.

I claim:

The ornamental design for a belt or similar article, substantially as shown and described.

CHARLES S. RAUCHER.
